ASH RECEPTACLE

Albert C. Grunwald, River Forest, Ill., assignor
to Precision Metal Workers, Chicago, Ill., a
corporation of Illinois

Application December 24, 1931
Serial No. 582,931

3 Claims. (Cl. 131—51)

This invention relates to ash receptacles, and particularly to ash receptacles which are provided with an ash tray or primary ash receiver from which the ashes and other light rubbish 5 may be dumped, at will, into the receptacle.

One of the objects of the invention is to provide an improved ash receptacle.

A further object of the invention is to provide an ash receptacle comprising a primary ash tray, 10 which is adapted to receive ash and light rubbish and discharge same into the receptacle while maintaining the receptacle sealed or substantially sealed so as to prevent the escape of fumes and odors from the receptacle.

15 Other objects, advantages and capabilities of the invention will appear from the following description of a preferred embodiment thereof, taken in conjunction with the accompanying drawing, in which

20 Figure 1 is an elevational view, partly in section, of an ash receptacle embodying my invention, the section being taken on line 1—1 of Fig. 2, and

25 Fig. 2 is a plan view partly in section, the section being taken on the line 2—2 of Fig. 1.

Referring to the drawing the reference numeral 10 indicates the receptacle, which may suitably be of metal. The receptacle may be supported on a standard 11 in known manner or it may be adapted to rest upon the table or other flat surface. The receptacle terminates at its upper end in a relatively large and preferably substantially cylindrical mouth formed by the wall 12. 30 This mouth is closed by a cover unit 13 which comprises a cylindrical wall 14 which is adapted to slide into the wall 12 and a bead or flange 15 which is adapted to engage the upper end of the cylindrical wall 12.

The cover unit comprises a dish-like element 16 which comprises a flat base 17 and the cylindrical wall 14 previously referred to. The upper edge of the wall 14 is bent outwardly to form a small flange 18. The cover element 13 also comprises the upper plate 19, the peripheral edge of which is spun over the flange 18 to provide the bead or flange 15 previously referred to. The base 17 is provided with an opening 20. The plate 19 is provided with an opening 21 which does not overlie the opening 20. As illustrated in the drawing the openings 20 and 21 may be substantially semi-circular in shape and may be located on either side of a diameter of the cover unit. It will be understood, however, that the invention is not limited to this particular size or shape of opening since, obviously, openings of different

sizes and shapes may be employed. It is not necessary, according to the invention, to make the openings 20 and 21 of the same size.

The upper plate 19 and the dish-like element 16 provide a housing 22 in which is located the 60 rotatable element 23. The rotatable element 23 comprises a plurality of compartments 24, two being shown in the drawing, which are open at top and bottom and which may suitably be formed of a strip of metal bent into configuration the 65 same or substantially the same as that of the opening 21. The compartments 24 may be slightly shallower than the housing 22 and the edge of the opening 21 may be spun downwardly 70 so as to make contact with the upper edge of the compartments. In the embodiment shown in the drawing the compartments 24 are secured in any suitable manner, for example by soldering, to a bridge member 25 which may suitably be a 75 length of tube of rectangular cross-section. A central stem 26 extends through the center of the bridge member 25 and is rigidly secured thereto, for example by soldering, so that the stem 26 may be employed to revolve the compartments 24. The stem 26 is provided with a 80 reduced lower end 27 which projects through a central opening in the base 17. The stem 26 projects upwardly through a boss 27' formed in the upper plate 19. The projecting end has rigidly mounted thereon a knurled button 28 whereby the rotatable element 23 may be rotated. 85

Cigar rests 29 are preferably mounted on the upper plate 19 and these rests may be located obliquely so that the burning ends of cigars or 90 cigarettes resting thereon may be located above the opening 21 so that ash dropping therefrom may fall into the primary ash tray constituted by the compartment 24 in register with the opening 21. In order to facilitate the attainment of exact 95 register between the opening 21 and the compartments 24 I mount a spring 30 on the base 17, which spring is provided with a projection 31 which is adapted to enter a depression 32 provided in each compartment 24. It will be understood that the projections 31 and depressions 32 are so located that exact register is readily obtained.

In the embodiment of the invention shown the boss 27' projects outwardly into the opening 21 and in order to provide a more perfect seal the inner walls of the compartment 24 are provided with outwardly bent central portions 33. As will readily be seen in Fig. 2 the bridge member 25 projects on either side of these outward bends and is there secured to the compartments 24 so 100 105 110

that a strong unitary revolvable structure results. In operation, the compartment 24 in register with the opening 21 and the portion of the base 17 below said opening constitute a primary ash tray for the reception of tobacco ashes and the like. When it is desired to dump the contents of the tray the revolvable unit 23 is revolved by the button 28 and the ashes and similar rubbish are swept over the base 17 by the wall of the compartment 24 until they are moved to the position of the opening 20 whereupon they fall into the receptacle 10. On account of the sweeping motion it is obviously unnecessary that the opening 20 should be as large as the compartment 24, provided it is sufficiently large to allow the intended rubbish to fall therethrough. The same revolving motion brings another compartment 24, or the same compartment 24, if desired, into register with the opening 21. The engagement of the projection 31 with the depression 32, which corresponds to exact register of the compartment 24 with the opening 21, may be felt by the operator's hand so that he is assured of correct manipulation.

25 The present invention provides an ash receptacle in which the main accumulation of ash and smoker's rubbish is substantially sealed at all times, both during normal use and during the transfer of rubbish from the primary ash tray 30 to the receptacle. In this way objectionable odors and fumes, and particularly those resulting from the charring of wax-paper matches in contact with lighted cigarette ends, are effectively prevented from passing into the room to the 35 annoyance of the occupants.

Although the invention has been described in connection with the specific details of preferred embodiments thereof, it must be understood that such details are not intended to be limitative of the invention, except insofar as set forth in the 40 accompanying claims.

Having thus described my invention, what I claim as new and desire to secure by Letters Patent is:

45 1. In combination, an ash receptacle, and a cover unit therefor, said cover unit comprising a housing having spaced substantially horizontal

walls provided with openings which are out of register, a downwardly extending flange around the periphery of the opening in the upper wall having an edge below the plane of the lower side of said wall, a revolving compartment within said housing having sufficient width to make substantially sealing register with said edge of said flange and engage the lower wall, and means pivotally mounting said compartment for rotation to ash discharging relation with the opening in the lower wall.

2. A cover for an ash receptacle comprising a housing having upper and lower substantially horizontal walls, said walls being provided with openings out of vertical register, a downwardly extending flange around the periphery of the opening in the upper wall, said flange being formed by the metal of the upper wall spun inwardly to provide an edge below the main portion of said wall, and a revolving unit comprising compartments having sufficient width to make substantially sealing register with said edge and with the lower wall, and means pivotally mounting said unit for rotation to bring each compartment from a position in register with said edge 100 to a position over the opening in the lower wall to discharge ash and other rubbish therethrough.

3. A cover for an ash receptacle comprising a housing having upper and lower substantially horizontal walls, said walls being provided with 105 openings out of vertical register, a downwardly extending flange around the periphery of the opening in the upper wall, said flange being formed by the metal of the upper wall spun inwardly to provide an edge below the main portion of said wall, a revolving unit comprising compartments having sufficient width to make substantially sealing register with said edge and with the lower wall, means pivotally mounting said unit for rotation to bring each compartment from 110 a position in register with said edge to a position over the opening in the lower wall to discharge ash and other rubbish therethrough, and resilient means for holding said revolving unit in said 115 registering position.

ALBERT C. GRUNWALD.
